REAR FOLDER FOR WRAPPING MACHINES

Stephen M. Bodolay, Springfield, Mass., assignor
to Package Machinery Company, Springfield,
Mass., a corporation of Massachusetts

Application November 4, 1940, Serial No. 364,164

15 Claims. (Cl. 93—2)

This invention relates to folding mechanism for wrapping machines. One standard method of wrapping consists in giving the wrapper a preliminary formation to provide parallel front and rear projecting flaps, the former of which is folded down by the passage of the article over a stationary folder, and the latter of which is folded down by a reciprocating plate movable faster than the article up to a point in close adjacency with the stationary folder. This reciprocating rear folder must move its full distance ahead before the article passes over the folding plate in order that the rear flap may be folded down before the movement of the article brings the front flap down on top of the rear one. Even though the rear folder is arrested in its forward movement and is not, as is customary, immediately drawn backwards; it will be seen that the continued forward passage of the article carries the rear flap over the surface of the stationary or backwardly moving rear folder in a direction opposite to that in which relative movement took place during the formation of the fold. This gives a tendency for the rear flap to become unfolded which becomes more pronounced in the case of non-rectangular articles such as for example lollipops having a generally globular shape. It is the object of the present invention to improve upon existing wrapping machines of this general type by providing a novel folding mechanism which will not exert this undesirable backward drag upon the rear flap. A further object of the invention is to provide a folding mechanism in which both the front and rear flaps may be tensioned at the time that they are folded one upon the other. Additional objects will appear from the following description and claims.

Before referring to the drawings in detail it may be stated that in accordance with the present invention the rear flap folder is formed of a flexible member, such, for example, as a plurality of interfitting segments, and traverses an endless path at a speed which is preferably constant. This path extends first in a direction parallel to that face of the article against which the rear flap is to be folded, the speed of the folder being greater than that of the article so that the leading end of the folder overtakes the rear flap and folds it down upon the face of the article. The path of the folder then diverges away from the article face, the point of divergence being as close as possible to the stationary folder. The length of the flexible folder in the direction of its path is sufficient so that even though its for-

ward portion has started to move away from the article in the diverging portion of the path, there will still be a part of the folder which is traveling along the straight portion of the path in contact with the rear flap. The folder at all times goes faster than the article, and thus a forward drag is exerted at all times upon the flap keeping it firmly folded in place. It is also preferable in some cases to cause the folder to engage the forward flap and to press it lightly against the stationary folder, the frictional wiping action thus obtained between the flap and the movable folder serving to cause this flap to be drawn tightly around the front edge of the article.

Referring to the drawings:

Fig. 1 is a side elevation of a rear folder mechanism for a wrapping machine constructed in accordance with the invention;

Fig. 2 is a fragmentary plan of a portion of this mechanism showing one form of construction of the flexible folder;

Fig. 3 is a section on an enlarged scale taken on line 3—3 of Fig. 2;

Fig. 4 is a section on line 4—4 of Fig. 1 showing the construction of certain timing mechanism;

Fig. 5 is a section on line 5—5 of Fig. 1;

Figs. 6, 7, and 8 are diagrammatic views showing the operation of the device; and

Fig. 9 is a similar view illustrating the device applied to an article of a different shape.

The wrapping machine itself has not been illustrated in detail as its construction does not relate to the present invention. The articles *a*, here shown as lollipops having a stick *s*, are fed along in any desired manner. In the case shown they are held upon plates *10* which may form parts of a conveying system and are held in position thereon by clamping members *11*. A wrapper *w* is folded around the article so as to provide one short flap and one long flap, the latter extending along the lollipop stick. By means of a pair of folders *12* which reciprocate vertically down and up during a rest period of the conveying system, the front and rear flaps *c* and *d* are folded as is shown in Fig. 6. As the conveying system carries the lollipops further ahead the flap *c* is folded by being passed over a stationary plate *13*. In prior machines of this type the flap *d* was folded by a plate reciprocating underneath the supporting plate *10* from a point to the rear of the folders *12* up to a position in adjacency with the stationary folder *13*.

In the present case the reciprocating rear

folder is replaced by a flexible folder comprising a plurality of folding members or segments 14 best shown in Fig. 3. These segments each have a convex forward end 15 and a concave rear end 16 so that they not only interfit to form a straight line folder as in Fig. 3 but also may form a substantially continuous curved folder as in Fig. 8. The individual segments are preferably in contact and form a continuous surface, but in general it will be sufficient if they are substantially contiguous and form a substantially continuous folder so that control of the rear flap is never entirely lost.

Each of the segments 14 is supported on a pintle 17 which projects laterally from a pair of parallel conveyor chains 18 and 19. As will appear from Fig. 1, the conveyor chains pass around sprockets 20 and 21, the latter of which is adjacent the stationary plate 13 and determines the curved part of the path of the folder. The chains also pass around guide sprockets 22, around driving sprockets 24, and around tensioning sprockets 25 acted upon by springs 26 so as to keep the chains constantly under tension. The driving sprockets 24 are driven by a chain 27 from a sprocket 28 on a drive shaft 29. As is best shown in Fig. 4, the drive sprocket 28 is fastened by clamp bolts 30 to a plate 31 in such a manner that the sprocket and the plate between them grasp the flange 32 of a member 33 carried on the shaft. By loosening the bolts 30 the angular position of the driving sprocket can be changed relative to the drive shaft 29, and the timing of the flexible folder with respect to the remaining portions of the wrapping machine can be adjusted.

As stated above, the pintles 17 extend between the two chains and project laterally beyond one side. It should be understood that only a portion of the entire length of the chains is provided with these pintles; it being necessary that the flexible folder, while possessing sufficient length to engage the rear flap until the forward flap is brought down firmly upon it, must have sufficient gap between its trailing and front ends along its endless path to permit the flaps to be folded downwardly into this gap as shown in Fig. 6. The chains run upon guide ribs 35, and are held down by ribs 36 on a cover plate 37. This may be sufficient to insure the accuracy of the pintles and the folders carried by them, but the pintles are preferably provided with hardened guide rolls 38 resting on or very slightly spaced from a guide rail 39 suitably secured to the frame of the machine. The rail is preferably provided only as a safeguard to prevent too great bending of the pintles away from the article the space between the guide rolls and the rails having been much exaggerated in the drawings for purposes of clarity. As a further means for insuring rigidity of the assemblage of segments, the pintles are preferably connected by short chains 60 and 61. These chains hold the segments snugly together, and the interfitting surfaces of the segments prevent any tendency towards misalignment.

The bracket 40 on which the guide ribs 35 and the sprockets 20, 21, 22, and 25 are carried is preferably made slideable on rods 41 and 42 extending laterally from a main support 43. An adjusting screw 44 is rotatably secured to the support by collars 45 and is threaded into a bracket 46 which slides on the rods 41 and 42. The adjusting screw has a hand wheel 47 by which the whole folder assembly can be shifted 75

toward or away from the stationary folder 13. The bracket 40 is mounted on ways 48 on the bracket 46 and the latter carries an adjusting screw 49 which is threaded into the bracket 40.

5 The latter adjusting screw has a hand wheel 50 by which the folding assembly can be moved up or down to cause the flexible folding member to make the contact desired with the folded flap of the article.

10 It is believed that the operation of the folding mechanism will be understood from the above description. As is shown in Fig. 6, the flaps c and d have been folded downwardly at a period in the cycle of the machine before the flexible folder has gone around into the position there shown. As the folder advances (which it will be remembered occurs during the advance of the article itself) its leading end folds the flap d underneath the article, as shown in Fig. 7, in the case illustrated folding the flap underneath the supporting plate 10 as well. When the article has partially passed onto the stationary folding plate and the rear flap d has been completely folded down, the flexible folder bends around its supporting pulley 21, as in Fig. 8, instead of stopping or retracting as in the case of the usual reciprocating rear folder. It will be noted that the folder keeps up its continuous motion and that its rear portion still contacts 20 with the flap d. This action, instead of causing the flap to loosen up, actually tightens it to a degree that can be regulated by adjusting the height of the folder by means of the hand wheel 50. If a tight wrap of the front flap c is also 25 desired, the flexible folder can be adjusted by means of the hand wheel 47 so that the flap c is pressed by the flexible folder against the stationary plate 13. This will keep a frictional drag on the flap and will cause it to be laid down very 30 tightly. It should be noted that this dragging action on the front flap can be brought about without in any way losing the tightness of the rear flap, the latter being pushed underneath the forward flap at all times until the latter has 35 come down upon it and firmly clamped it in place.

The folding mechanism as above described is of course susceptible of many changes. Instead of using an articulated member as shown the 40 folding plate could be made from a piece of flexible leather belting. In general, however, to avoid the strains incident upon repeated bending of a single piece of material it is preferable to use a jointed piece as shown. Other changes 45 may be made in order to accommodate the device to articles of different shape. For example, Fig. 9 shows a lollipop m of generally globular shape supported on a curved plate or spoon 55. The flaps are formed and folded exactly as in the preceding case. This particular form of article is one of extreme difficulty to wrap since the wrapper cannot be tightly drawn down the sides and since the bottom is curved. By the use 50 of the folding construction described, a sufficient forward pressure is kept on the rear flap at all times to keep this flap from being turned backwardly by the rearward drag of the front flap. In Fig. 9 a modified setting of the folder is shown, the latter not being in this case pressed against the stationary folder 13. Many other changes may be made in accordance with the special nature of the article or machine to which the device is applied.

I claim:

1. A folder for wrapping machines and the like

which comprises a flexible member and means for moving the member in an endless non-circular path extending past one face of the article and then diverging sharply from said face.

2. In a wrapping machine of the type in which an article with projecting front and rear flaps is moved past a stationary front flap folder, a rear flap folder comprising a flexible member, and means for moving said member at a speed faster than that of the article in a path extending past one face thereof and towards the stationary folder and diverging from the path of said article face adjacent the stationary folder.

3. In a wrapping machine of the type in which an article with projecting front and rear flaps is moved past a stationary front flap folder, a rear flap folder comprising a flexible member and means for moving said member at a speed faster than that of the article in a path extending past one face thereof and towards the stationary folder and diverging from the path of said article face adjacent the stationary folder, and in close enough proximity thereto to cause pressure of the front wrapper flap against said stationary folder.

4. In a wrapping machine of the type in which an article with projecting front and rear flaps is moved past a stationary front flap folder, a rear flap folder comprising a conveyor, a flexible folder projecting laterally from the conveyor, and means for moving the conveyor in an endless path carrying the flexible folder past one face of the article and diverging sharply from the article face adjacent the stationary folder.

5. In a wrapping machine of the type in which an article with projecting front and rear flaps is moved past a stationary front flap folder, a rear flap folder comprising a conveyor, a flexible folder projecting laterally from the conveyor, means for moving the conveyor in an endless path carrying the flexible folder past one face of the article and diverging sharply from the article face adjacent the stationary folder, and means for adjusting the conveyor toward and away from the stationary folder to cause said flexible folder to press the front wrapper flap with a regulable pressure adjacent said stationary folder.

6. In a wrapping machine of the type in which an article with projecting front and rear flaps is moved past a stationary front flap folder, a rear flap folder comprising a conveyor, a plurality of pintles projecting laterally from the conveyor, a plurality of folding members mutually articulated and one mounted on each of said pintles, and means for moving the conveyor in an endless path carrying the assemblage of folding members past one face of the article and diverging sharply from said article face adjacent the stationary folder.

7. In a wrapping machine of the type in which an article with projecting front and rear flaps is moved past a stationary front flap folder, a rear flap folder comprising a pair of spaced endless chain conveyors, a plurality of pintles projecting laterally from a portion only of the length of the chains, a plurality of contiguous mutually articulated folding members carried by said pintles, guiding means supporting said pintles for movement in a predetermined path, and means for moving the chains at a speed faster than that of the article to carry the folding members as a unit in a path extending past one face of the article and in a direction toward the stationary folder, said path then diverging from the path of

the article face at a point adjacent the stationary folder.

8. In a wrapping machine of the type in which an article with projecting front and rear flaps is moved past a stationary front flap folder, a rear flap folder comprising a pair of spaced endless chain conveyors, a plurality of pintles projecting laterally from a portion only of the length of the chains, a plurality of contiguous mutually articulated folding members carried by said pintles, guiding means supporting said pintles for movement in a predetermined path, flexible chains interconnecting the pintles on either side of the folding members, and means for moving the chains at a speed faster than that of the article to carry the folding members as a unit in a path extending past one face of the article and in a direction toward the stationary folder, said path then diverging from the path of the article face at a point adjacent the stationary folder.

9. In a wrapping machine of the type in which an article with projecting front and rear flaps is moved past a stationary front flap folder, a rear flap folder comprising a pair of spaced endless chain conveyors, a plurality of pintles projecting laterally from a portion only of the length of the chains, a plurality of contiguous mutually articulated folding members carried by said pintles, guiding means supporting said pintles for movement in a predetermined path, means for moving the chains at a speed faster than that of the article to carry the folding members as a unit in a path extending past one face of the article and in a direction toward the stationary folder, said path then diverging from the path of the article face at a point adjacent the stationary folder.

10. In a wrapping machine of the type in which an article with projecting front and rear flaps is moved past a stationary front flap folder, a rear flap folder comprising a flexible member, and means for moving said member continuously at a speed faster than that of the article in an endless path extending past one face thereof and in a direction toward the stationary folder, said path diverging from said article face adjacent the stationary folder, the length of the flexible member in the direction of its endless path being limited sufficiently to permit the flaps to be moved into a position crossing the path of the folder.

11. In a wrapping machine of the type in which an article with projecting front and rear flaps is moved past a stationary front flap folder, a rear flap folder comprising a flexible member, and means for moving said member continuously at a speed faster than that of the article in an endless path extending past one face thereof and in a direction toward the stationary folder, the extent of said folder in the direction of its endless path being sufficient to permit the folder to remain in contact with the rear article flap until the front flap has been folded at least partially on top of it.

12. In a wrapping machine of the type in which an article with projecting front and rear flaps is moved past a stationary front flap folder, a rear flap folder comprising a flexible member, and means for moving said member continuously at a speed faster than that of the article in an endless path extending past one face thereof and in a direction toward the stationary folder, the

extent of said folder in the direction of its endless path being sufficient to permit the folder to remain in contact with the rear article flap until the front flap has been folded at least partially on top of it but limited sufficiently to permit the flaps to be moved into a position crossing the path of the folder.

13. A folder for wrapping machines and the like comprising a flexible member of finite length, and means for moving the member in an endless unidirectional path in part contiguous to but lying in a plane at right angles to the plane of a face of the article to be wrapped, and then diverging abruptly from said article face, whereby the leading edge of the member may strike and 15 fold down a wrapper flap projecting from the article and the surface of the member may continue to wipe against the folded down flap after said leading edge has diverged therefrom.

14. A folder for wrapping machines and the like comprising a flexible plate-like member of finite length, and means for moving the plate-like 20

member in a unidirectional endless path having a plane portion extending parallel to but lying in a plane at right angles to the plane of a face of the article, and a subsequent portion diverging sharply from said plane of the article face and causing bodily bending of the flexible plate-like member, whereby the leading edge of the member may strike and fold down a wrapper flap projecting from said face of the article and the surface of the member may continue to wipe against the folded down flap after said leading edge has diverged therefrom.

15. In a wrapping machine or the like, a folder of finite length and means constraining it for movement in a non-circular unidirectional endless path wholly external to the article when the latter is in folding position and in part contiguous to and conforming to but lying in a plane at right angles to the plane of a face of the article to carry the folder unidirectionally past said article face.

STEPHEN M. BODOLAY.
